UNITED STATES PATENT OFFICE.

JOHN E. ATWOOD, OF STONINGTON, CONNECTICUT.

WINDMILL.

SPECIFICATION forming part of Letters Patent No. 548,171, dated October 22, 1895.

Application filed October 9, 1893. Serial No. 487,707. (No model.)

To all whom it may concern:

Be it known that I, JOHN E. ATWOOD, a citizen of the United States, and a resident of Stonington, in the county of New London and State of Connecticut, have invented certain new and useful Improvements in Windmills, of which the following is a specification.

My invention relates to windmills designed to run by belts and pulleys, dynamos, and other fast-moving machinery.

The object of my invention is to provide a windmill that shall be strong, efficient, and yet inexpensive in its construction. These ends I attain by the novel combination of instrumentalities described and claimed.

Figure 1 is a rear elevation of my improved windmill, showing its principal parts. Fig. 2 is a side elevation of the same. Fig. 3 is a sectional plan view on line xx of Fig. 2 of the power-transmitting pulley and the sheaves or idle-wheels over which pass the driving belt or rope from the wind-wheel to the power-transmitting pulley. Fig. 4 is a sectional view on line yy of Fig. 3 of the ratchet-hock which connects the power-transmitting pulley with the power-receiving pulley. Fig. 5 is a detailed vertical section, enlarged, of the standard and the main parts of the frame. Fig. 6 is a front view of the supporting-hub of the windmill-wheel. Fig. 7 is an enlarged sectional view at right angles to the view in Fig. 6 of the hub and the inner ends of the vanes and vane-braces. Fig. 8 is a front elevation of parts similar to those shown in Fig. 7. Fig. 9 is a sectional view on line zz of Fig. 7, showing a portion of the segmental bracket and the lugs integral therewith. Fig. 10 is a top or plan view of the cap at the top of the standard or tube, showing the upper ends or inner extremities of the guy-ropes which support the windmill in an upright position. Fig. 11 is a cross-sectional vertical view of the parts similar to those shown in Fig. 10. Fig. 12 is a detail cross-section of the periphery of the windmill-wheel. Fig. 13 is a detail sectional plan view on line $z'z'$, Fig. 5. Fig. 14 is a plan view of the oil-box located at the end of the spindle carrying the windmill-wheel, oil being carried from said box to the sleeve supporting the wheel by means of a spiral cut in the sleeve. Fig. 15 is a vertical sectional view

of the oiling-sleeve of the power-transmitting or work pulley.

Referring to Figs. 1, 2, and 5 of the drawings, A indicates the stationary vertical shaft 55 or standard of the windmill, which is ordinarily an iron tube, which is inserted or driven in the ground a certain distance, depending upon the circumstances of the case. This standard or tube has around its lower end another tube A', which strengthens the tube A. This strengthening-tube A' supports at its upper end a collar A'', which in turn supports the lower end of a sleeve B, which is arranged to turn on the shaft A, so as to bring the windmill into proper position with relation to the wind. The sleeve B has secured to it near its center a horizontal spindle C. This spindle is preferably formed integral with a sleeve C', which is slipped over and secured to the sleeve 70 B at a point near its center. On this horizontal spindle C, arranged to turn freely on it, is a sleeve D, which carries or has formed integral with it the hub E, which carries the vanes of the windmill-wheel W. This sleeve 75 D is prevented from sliding longitudinally to the inner end by a shoulder d on the spindle C. This shoulder d is preferably formed integral with C. At the other end movement is limited by the inner wall d' of the oil-box D'. 80

The oil-box D' is, as shown in Figs. 5 and 14, clamped onto the horizontal spindle C by the cap C². (Shown in Fig. 14.) The cap C² is secured to the box D' by bolts or other suitable securing devices. At the end of the oil-box are formed two lugs c c, engaging in grooves c' c' in the end of the spindle C, which prevent a lengthwise movement of the oil-box. The hub E may be formed integral with the sleeve D or may be attached thereto rigidly in any well-known manner. 85 90

The vanes F of the windmill-wheel W are attached to the hub E in the following manner, attention being called to Figs. 5 to 8, inclusive: To the hub E is attached, by bolts 95 b, a disk E'. The vanes F are held between the hub E and the disk E', these vanes of course being at an angle to the axis of the wind-wheel. Small chambers may be cut in or lugs may be cast on the inner faces of E 100 and E', so as to hold the vanes in place. On the inner periphery of E and E' are formed

lugs f^6 for holding the bolts which keep the vanes F in position. Bolted by the bolts e to the spokes of the wheel or hub E are the vane-braces F' . These braces F' have, at 5 different distances from the center of the wheel, bolted to them double sets of segments F^2 and F^3 by the bolts f . Each set of double segments has the segments arranged so as to break joints, and these segments, as is evident, form complete strengthening rims or circles for the rods F' . The vanes F are attached to these strengthening rims or circles F^2 and F^3 by means of lugs f^4 , (shown in Fig. 9,) cast on segments F^2 and F^3 , these lugs being of different lengths in each pair, respectively, so as to insure the angular position of the vanes of the wind-wheel.

Attached to the top of the sleeve B is a vane-frame H , carrying the vane H' . This 20 vane-frame H is composed of a short sleeve h and a thimble h' . This sleeve h may be attached to the vane H' in any well-known manner or may be formed integral therewith. The thimble h' is bolted to H' , and, as shown, 25 it surrounds the shaft A . Attached to H' is a rod or wire rope H^2 , whose lower end is looped around the lip c^8 on the spindle C . It is evident that the function of the vane H' is to keep the windmill in a proper direction 30 in relation to the wind. At the upper end of the tube or standard A is inserted a cap I , having a shoulder thereon for holding it on top of the tube. The upper guy-ropes I' , which help to keep the windmill in an up- 35 right position, have loops i formed at their ends, which are placed over the lugs i' on the cap I . A washer i^2 is placed over the inner ends of these loops and lugs and screwed down thereon by a screw i^3 . The guy-ropes 40 I^2 , supporting the lower part of the framework, are held in position in the following manner: The guy-ropes have heads or extensions i^4 , which fit in sockets i^5 in the oil-cup L^3 , (the heads and sockets being similar to 45 those of the truss-rods and their supports,) which is sleeved on or otherwise affixed to the tube A' .

K is a frame surrounding and attached to the sleeve B . This frame K has arms K' , which, in turn, have pivoted to their ends adjustable supports K^2 , carrying the sheaves or idlers K^3 . As shown in Fig. 3, these supports K^2 are adjusted or capable of adjustment by means of adjusting-rods K^4 , which have on 55 their inner ends screw-threads, which work in and out of the brackets K^5 . The purpose of this adjustment is to enable the tightening and slackening of the power-transmitting rope or belt P , which passes over K^3 from 60 W to the pulley L .

L is a pulley which turns freely on the sleeve L' , which is between it and the tube A' , whose lower end rests in an oil-cup L^3 , which is rigidly fixed to the strengthening- 65 sleeve L' . This sleeve L' has cut on its inner periphery a spiral channel, which con-

veys the oil from the oil-box L^3 when L is revolving to lubricate the entire length of the bearing. A pulley L^2 is fixed to the sleeve L' and transmits motion to any machinery by 70 a belt or rope. The pulley L^2 may be clutched to the pulley L by any means, such as the hook M . As shown in Figs. 3 and 4, M is pivotally attached at one end to a spoke of the pulley-wheel L , and at the other end on 75 M is a hook, which engages with another spoke of L . As shown, M is so shaped that a hook m , near its middle, engages with one of the spokes of L^2 when M is down, thus positively connecting L with L^2 , in which case the pulleys move together and power is carried by 80 L^2 to any appropriate machinery.

The windmill-wheel W has on its periphery a leather friction-rim N , fastened down by guides N' . These guides are composed of 85 peripheral flanges, which are bolted to the periphery of the wheel W . N' is made in segments.

A belt or power-transmitting rope P passes over the periphery of the windmill-wheel W , 90 over the idler or sheaves K^3 , around the pulley L , and back again to W .

The windmill-frame is additionally strengthened by the truss-rods Q Q , which have on their ends heads or extensions q , which fit 95 into sockets q' in the inner ends of the frames H and K . These truss-rods are held out in the middle by the struts Q' and the collars Q^2 , formed on the spindle C . The struts Q' and the collar Q^2 may be either integral with 100 the spindle C or may be attached thereto in any well-known way. These truss-rods Q Q pass through what might be called "openings" 105 in the said struts and collar—that is, they may pass through holes therein or grooves 110 therein, as the case may be. Horizontal truss-rods Q^3 are also connected to the spindle C , as shown in Figs. 1, 2, and 5, and they are affixed in practically the same way as the vertical truss-rods Q —that is, by having heads 115 at their ends which fit in the struts Q' and the collar Q^2 , forming parts of the spindle C , by sockets similar to those in the vane and idler frames. Figs. 5 and 13 show plainly in 120 cross-section how these heads or extensions 125 q fit into the sockets q' .

As shown in Fig. 5, the means by which oil is conveyed from the oil-box D' to the sleeve D are as follows: On the inner periphery of the sleeve D is cut a spiral channel d^2 , by which 120 the oil is carried up and along the sleeve to a hole on the inner and upper part of the spindle C , through which hole the oil drops down into the hollow spindle and flows along back to the oil-box D' . Of course as the oil passes 125 along through the channel d^2 it fully lubricates the inner surface of the sleeve D . Similar oil-cups, with sleeves having spiral grooves to carry the oil along, are used with the idler-wheels K^3 , as shown in Figs. 1 and 3 at k^5 .

Although I have set forth my invention 130 fully in detail, and although it is composed of

improvements in different parts of a windmill by which said windmill is rendered much more efficient, yet I regard well-known modifications and mechanical changes, such as would occur to one skilled in the art, as entirely within the scope of my invention.

One of the purposes to which this windmill could be applied would be, especially in districts lacking fuel, to run dynamo-machines during the times that wind furnishes sufficient power and to charge secondary batteries by these dynamos, thus storing energy which could be taken off at any time when required to furnish light, heat, and power constantly and for a considerable period of time.

I claim—

1. In a wind-mill apparatus, the combination of a vertical shaft or tube, a sleeve thereon carrying the wind-wheel apparatus, a frame carrying a vane at the upper part of said sleeve, and a frame carrying idlers at the lower part of the sleeve, truss rods connecting the vane frame and idler frame together, said truss rods having heads or extensions on their ends, and sockets in the inside ends of the vane and idler frames to hold the heads of the truss rods.

2. In a wind mill apparatus, the combination of a vertical shaft or tube, a sleeve thereon carrying the wind wheel apparatus, a frame carrying a vane at the upper part of said sleeve, a frame carrying idlers at the lower part of the sleeve, and truss rods connecting the vane frame and the idler frame together, substantially as described.

3. In a wind-mill apparatus, the combination of a vertical shaft or tube, a sleeve thereon carrying a horizontal spindle, a wind-wheel carried by the said spindle, an oil-box having lugs or extensions fitting into grooves or depressions in the spindle, and a cap to hold the oil-box rigidly to the spindle and to prevent longitudinal movement of the wind-wheel hub.

4. In a wind-mill apparatus, the combination of a vertical shaft or tube, a sleeve thereon carrying a horizontal spindle, a wind-wheel carried by the said spindle, a vane frame attached to the said sleeve, and a rod or outside support extending from the vane frame to the end of the wind-wheel spindle.

5. In a wind-mill apparatus, the combination of a vertical shaft or tube, a sleeve thereon carrying a horizontal spindle, a wind-wheel carried by the said spindle, a vane frame attached to the said sleeve, and a rod or outside support extending from the vane frame to the end of the wind-wheel spindle, and a lip on the end of the spindle, for keeping the rod or support in place.

6. In a wind mill apparatus, the combination of a vertical shaft or tube, a sleeve thereon carrying the wind wheel apparatus, a frame carried by the lower part of the sleeve and pivotally connected therewith, idle pulleys carried by said frame, a driving pulley sup-

ported below the idler frame, a driving belt passing over the wind wheel, the idlers and the driving pulley, and another pulley connected with the driving pulley for communicating motion to the object to be driven.

7. In a wind-mill apparatus, the combination of a vertical shaft or tube, a sleeve thereon carrying the wind-wheel apparatus, a spindle extending from said sleeve, truss rods connected to the upper and low ends of the said sleeve, the said truss rods passing through vertical openings in the wind-wheel spindle, and other truss rods attached to the horizontal spindle and passing through horizontal openings in the part of the spindle near the main supporting sleeve.

8. In a wind-mill apparatus, the combination of a vertical shaft or tube, a sleeve thereon carrying a horizontal spindle, a wind-wheel carried by the said spindle, pulleys carried below the lower part of said sleeve, one of said pulleys being positively connected with the wind-wheel, the other being loose on the shaft or tube, and a hook or clutch for connecting the two pulleys to each other so that they move in unison.

9. In a wind-mill apparatus, the combination of a vertical shaft or tube, a sleeve thereon carrying a spindle, a wind-wheel carried by said spindle, the periphery of the wind-wheel having upon it a separate friction surface and guides whereby the driving belt is retained on the wind-wheel, said guides serving to secure the friction surface to the wheel proper.

10. In a wind-mill apparatus, the combination of a vertical shaft or tube, a sleeve thereon carrying a horizontal spindle, which spindle carries the wind-wheel, an oil-box rigidly attached to said spindle, a spiral groove in the wind-wheel hub or on the hollow spindle, said spindle having an opening or openings therein for the return of the oil from the opening to the oil-box, said spindle being hollow.

11. In a wind mill apparatus, the combination of a vertical shaft or tube, a sleeve thereon carrying the wind wheel apparatus, a frame at the lower part of said sleeve pivotally connected therewith, rods pivotally connected with said frame, idlers carried by the rods, and adjusting rods and levers to regulate the position of the idlers so as to control the tension of the driving belt.

12. In a wind-mill apparatus, the combination of a vertical shaft or tube, a sleeve thereon carrying the wind-wheel apparatus, a collar below the said sleeve on the said shaft, and a strengthening sleeve or tube on the lower part of the shaft for supporting the wind-mill sleeve.

13. In a wind-mill apparatus, the combination of a vertical shaft or tube, a sleeve thereon carrying the wind-wheel, the said wind-wheel having a hub which carries the vanes, vane braces carried by the said hub and bolted thereto, segments bolted to the said braces at

different distances from the center of the wheel, each set of segments forming a complete bracing circle or rim, the said bracing circles or rims being bolted to the vanes.

- 5 14. In a wind-mill apparatus, the combination of the following elements forming a wind-wheel: a hub, vane braces bolted to said hub, a disk bolted to said hub for holding the inner ends of the vanes in place, double sets of segmental pieces which break joints, bolted to the several vane braces so as to form strengthening rims or circles, there being different

strengthening rims or circles from the center of the wheel outward, projections on the faces of the segments to which are bolted the vanes 15 of the wind-wheel.

Signed at Stonington, in the county of New London and State of Connecticut, this 3d day of October, A. D. 1893.

JOHN E. ATWOOD.
